UNITED STATES PATENT OFFICE.

MERRILL W. HARD, OF DETROIT, MICHIGAN, ASSIGNOR TO THE MATLICK TELLURIAN CO., OF SEATTLE, WASHINGTON, A CORPORATION OF OREGON.

TELLURIAN.

1,259,731.

Specification of Letters Patent. Patented Mar. 19, 1918.

Application filed October 23, 1916. Serial No. 127,064.

To all whom it may concern:

Be it known that I, MERRILL W. HARD, a citizen of the United States, residing at Detroit, in the county of Wayne and State 5 of Michigan, have invented certain new and useful Improvements in Tellurians, of which the following is a specification.

This invention relates to tellurians and, more especially, to improvements in the apparatus of this character shown and described in U. S. Patent No. 1,019,981, issued to I. N. Matlick March 12, 1912.

The object of the present invention is the perfecting of such apparatus to render the 15 same more convenient to manipulate and peculiarly serviceable for illustrating to students of astronomy certain movements of the earth and the moon with respect to each other or with relation to the sun.

With these ends in view, the invention 20 consists in the novel construction, adaptation and combination of parts of the operating mechanism of a tellurian, as will be herein-after described and claimed.

In the accompanying drawings, Figure 1 25 is a perspective view of a tellurian embodying my improvements. Fig. 2 is a view partly in plan and partly in horizontal section of the same, said section being taken substantially through 2—2 of Fig. 3, and the cover-plate from the rack-casing omitted. Fig. 3 is a fragmentary view shown 30 partly in side elevation and partly in vertical section of the support for the frame of the earth and moon spheres and illustrating the releasable driving connections therefor to enable the referred to spheres to be operated in their orbital travel about the sun sphere or independently of the latter and 35 about an axis representing their common center of gravity. Fig. 4 is a detail section through 4—4 of Fig. 2.

The reference numeral 5 designates a table or stand upon which is rigidly secured a 40 frame having a centrally disposed post 6 and a plate 6¹ which is formed to provide concentrically arranged rack and rail elements 6² and 6³. Journalized on said post is the hub 7 of a rotary frame in the nature of a wheel whose annular rim 7¹ is integrally 45 connected by radial spokes 7² to the hub.

Adjacent to the rim said spokes are chambered, as at 7³, to accommodate toothed pinions 8 and 9 which engage said rack element, 50 and are secured to a stub-shaft 10 and a

main shaft 11 disposed, preferably, in axial alignment with each other.

Said pinions are, moreover, formed with peripheral ridges 8¹ and 9¹ to respectively track upon the aforesaid rail element 6³ and 60 serving as anti-friction roller supports for the rotary frame. The shaft 10 is journaled, as indicated by 10¹ and 10², in the adjacent spoke and a sleeve 7⁴ protruding radially from the frame rim 7¹. Outside of said 65 sleeve the shaft 10 is provided with a wheel 10³ having a crank-handle 10⁴ whereby said rotary frame may be most conveniently rotated through the agency of the pinion 8 and rack element 6².

A cover-plate 12, Fig. 1, is detachably secured upon the post 6 by a screw 13 extending through an aperture in the cover and engaging in a threaded hole 14 in the post 6. 70 15 is a standard extending upwardly from the cover-plate to support the sun sphere S.

At the diametrically opposite side of the frame rim 7¹ from the sleeve 7⁴ is a second sleeve 7⁵ which affords a socket for a tubular arm 17 to which it is removably secured by 75 a set screw 17¹.

Fitted to and rigidly secured on the outer end of the arm 17 is the branch 18 of a yoke piece 18¹ having another branch 18² which is bored to serve as the bearing for the tubular hub 19 of a bevel pinion 19¹. The above mentioned shaft 11 is journaled at one end, as at 20, in a spoke of the rotary frame and also in a bushing 17² provided in said arm, and thence extends into the axial bore 80 of the pinion hub 19.

The part 11² of the shaft which extends through and beyond the hub 19 is of less diameter than the remaining part of the shaft and at the outer end of its reduced 85 portion is screw threaded to receive a thumb nut 21.

The shoulder 19³ obtaining on the shaft and the adjacent end 19² of the pinion hub are knurled to provide inter-engageable surfaces which, upon being juxtaposed by suitably influencing the pinion through the medium of the thumb-nut, will effect the coupling of the pinion to the shaft. When the thumb-nut, however, is retracted and the hub 100 disengaged from the knurled shoulder of the shaft, the pinion 19¹ is rotatable independently of the shaft. This pinion meshes with a beveled toothed gear 22 secured to the lower end of an upright shaft 22¹ which 105 110

is journaled in the yoke piece 18¹ and carries the frame member 23 by which the earth and moon spheres E and M are carried together with the operating mechanism which 5 is actuated through the instrumentality of the shaft 22¹ when the latter is coupled with and operated through the medium of the shaft 11 when the latter is rotated in its revolution with said rotary frame.

10 The above-referred-to mechanism including trains of gears 28, for effecting the co-operative movement of the earth and moon spheres, are substantially similar in construction, arrangement and mode of operation to 15 that illustrated in the aforesaid patent. It may be mentioned, however, that the earth sphere E rotates on an inclined axis rod 24, and the moon sphere M is supported for revoluble and vertical movements upon the 20 outer arm 25 of a lever which is fulcrumed at 26 and having its other arm 25¹ engage with a rotary cam 27 whereby the vertical movements of the moon sphere are effected as it is revolved about the axis of the upright 25 shaft 22¹ in the rotation of the frame 23.

The shaft 22 is located so that the axis thereof when projected will extend through the assumed center of gravity of the earth and moon spheres and about which they 30 take their orbital courses in addition to their orbital travel about the sun sphere.

The operation of the invention will, it is thought, be understood from the foregoing description.

35 Among the advantages due to my improved devices are, first, the facility and smoothness of operation of the movable parts of the apparatus derived through the employment of a cranked wheel 10³ to impart rotary motion to the rotary frame by means of a pinion 8 engaging a rack to propel thereby such frame instead of doing so directly, as hitherto; second, to the use of 40 roller elements 8¹ and 9¹ on the driving and driven pinions 8 and 9 to roll upon the circular track 6³ for not only supporting the rotary frame but also serve to prevent the teeth of such pinions from undue frictional engagement with the circular rack; third, to the manner or means of disengaging the 45 bevel gear 19¹ from the shaft 11 to enable the earth and moon spheres and the mechanism associated therewith to be operated without traveling about the sun sphere to more clearly demonstrate various phenomena 50 relating to these bodies and their co-operative actions and mutual influences irrespective of the sun sphere.

What I claim is—

60 1. In a tellurian of the character described, a non-rotatable circular rack, a rotary frame, a main shaft and a stub shaft carried by said frame, a pinion mounted upon each of said shafts, and means provided on said stub shaft to effect the rotation of said frame

through the agency of the respective pinion and said rack whereby the latter actuates the other pinion to impart rotary motion to the main shaft as it is revolubly carried by said frame.

70

2. In a tellurian of the character described, a stationary plate formed with circular rail and rack elements, a stationary post disposed concentrically of said circular elements, a frame connected to said post for rotary movement, rollers tracking on said rail and supporting said frame, toothed gears rotatable in unison with the respective rollers, a main shaft connected to one of said gears whereby the shaft is rotated in the revoluble travel of such gear on the rack, and means for rotating the other of said gears and coacting with said rack to impart rotary motion to the frame.

75

3. In a tellurian of the character described, a stationary circular rack, a post centrally thereof, a frame journaled on said post, a stub shaft disposed radially of and journaled in said frame, a main shaft journaled in said frame in axial alinement with the aforesaid shaft, toothed gears engaging said rack and mounted on the respective shafts, and a hand wheel carried by said stub-shaft for rotating the associated gear to impart rotary motion to the frame which, in turn, actuates the second gear to rotate the main shaft.

80

4. In a tellurian having a relatively stationary sphere representing the sun, bodies representing the earth and moon arranged to revolve about an axis intermediate of each other and also about said sphere, mechanism rendered operative in the revolution of said bodies about the sphere to effect the revolutions of the bodies about said axis, and means included in said mechanism whereby the revolutions of said bodies about the axis may be effected without their revolving about said sphere.

85

5. In a tellurian of the character described, the combination with a relatively stationary sphere representing the sun, a stationary circular rack, a frame rotatable concentrically of said rack, a sleeve extending from said frame, a yoke secured to the outer end of said sleeve, bodies representing the earth and moon, a support for said bodies carried by the yoke, and rotatable on an upright shaft disposed intermediate the axes of said bodies, and mechanism for rotating the earth body on its axis and to effect the rise and fall of the moon body in an inclined elliptic, of a main shaft extending through said sleeve, a toothed gear mounted on said shaft to engage said rack to impart rotary motion to the shaft during the rotation of said frame, a pair of gears for transmitting rotary motion from said main shaft to said upright shaft to actuate said mechanism, and means whereby said pair of gears may be rendered temporarily inoperative to enable said mech-

90

130

anism to be operated to influence said bodies independently of rotation of said frame.

6. In a tellurian of the character described, the combination with the sun sphere, spherical bodies representing the earth and moon, means to actuate said bodies to perform their relative motions with respect to each other, means to revolubly carry said bodies about said sphere, and means whereby the referred
10 to motions of said bodies are operable in unison with or independently of their revolu-

tions about the sphere, said means also serving to enable the bodies to be revolved about the sphere without having imparted thereto any relative motions between the two bodies. 15

Signed at Detroit, Michigan, this 12 day of October, 1916.
